DEVICE FOR DIVIDING COINS INTO GROUPS
AND FOR PACKING SUCH GROUPS

Albert Frei, Zurich, Switzerland

Application August 28, 1950, Serial No. 181,892
In Switzerland September 6, 1949

8 Claims. (Cl. 133—8)

1

The invention relates to a device for dividing coins into groups and for packing such groups. Devices for counting coins and packing them in paper rolls are already known. In their simplest form, they consist of one or more counting channels of a length corresponding to a particular number of coins of a particular size arranged side-by-side. Devices of the same kind are also known in which counting channels are juxtaposed transversely or upwards and of a length such that they can each receive a number of coins of a particular size, for example 1 to 10 pieces. All these devices require the coins to be laid carefully into the channel shaped subdivisions, which is troublesome particularly when much money is being handled. Moreover, the packing involves the rolling up of the coins in paper. Consequently, the coins cannot be seen and there is therefore no guarantee that the contents correspond with the indication of value given on the paper roll. In order to overcome that disadvantage, trough-like divisions exist which have been provided with a stirrup-like locking member so that the coins in the divisions can be seen and transported. When using such devices, the coins must first of all be counted which is effected by placing them in the juxtaposed receiving spaces or by the use of coin caskets subdivided by plates. Experience has shown, however, that such devices are too expensive to enable them to be generally used.

The object of the invention is to provide a device of the kind referred to above which makes possible both a rapid subdivision of coins of a particular value into groups and packing of the groups in such a way that the packed coins remain at all times visible and divided. To this end, in a device constructed in accordance with the invention for the subdivision and packing of coins of at least one size into groups, there are provided a wedge shaped longitudinally displaceable pusher in the form of a right-angled triangle, a coin container which can be displaced by the pusher in a stationary guide, a longitudinally slotted dividing plate arranged in the direction of the inclined plane of the pusher at the upper part thereof and having a number of holes in it arranged side-by-side in the direction of its length, and a number of guide rails corresponding to the number of holes in the dividing plate and arranged one above the other beneath the dividing plate and slotted in the direction of their length. The ends of the guide rails lie, on one side, one above the other, while on the other side, they each extend up to the associated hole

in the dividing plate. Further, a fixed ejector is provided which, when the wedge-shaped pusher is actuated, passes through the superimposed slots in the hole plate and the guide rails and pushes the groups of coins, which fall out of the coin container through the holes in the dividing plate and have all the same height, at first along said guide rails and thereupon into a holder. The holder can be removably attached to the ends of the guide rails, which lie one above the other, and has a number of divisions corresponding to the number of holes in the dividing plate, the coins pushed into these divisions being always visible and countable.

15 An example of construction of a device in accordance with the invention is shown, partly in simplified fashion, in the accompanying drawings in which

Fig. 1 is a sectional elevation of a device for dividing up and packing coins which do not differ greatly in diameter so that for each operative movement to be carried through in the device, only coins of the same size can be placed in the device.

20 Fig. 2 is a plan of the device.

Fig. 3 is a sectional elevation of a coin container, of a trough pivotally connected to the container and shown in the horizontal position for receiving the coins and also of a dividing plate which is embraced by a stirrup-like base of the coin container.

Fig. 4 is a plan of Fig. 3.

Fig. 5 is a plan of a stepped pile of guide rails which serve for guiding already subdivided groups of coins.

Fig. 6 is a diagrammatic view of a coin holder with five coins of the same size ejected into its uppermost division, and

Fig. 7 is a plan of a modification of a detail.

In the drawings, 1 designates a wedge-shaped pusher of substantially right-angled triangle shape which is arranged for longitudinal displacement in the horizontal direction in a U-shaped base plate 2. On the base plate 2 are fixed two vertical guides 3 which serve for guiding a coin container 4. This container 4 has a hole 6 extending from its upper end to its base 5. The hole 6 is of circular cross section and its diameter is only slightly greater than that of the coins which are to be sub-divided and packed in the device. On the coin container 4 is pivotally mounted a trough 7 which has an open groove for receiving the coins which extends over the whole of the length of the trough. The groove of this trough 7 is divided by a transverse par-

tion 7¹ into two sections, the length of the section lying to the left of the transverse partition 7¹ being practically equal to the length of a pile of coins which is to be packed at each operative stroke of the device. The other section of the groove serves for receiving coins serving, for example, for exchange. The coins inserted into the groove of the trough 7 can be fed therefrom into the hole 6 of the coin container either by tipping the trough 7 upwards or by hand or by both methods.

Parallel to the inclined plane of the wedge shaped pusher 1, a divided plate 9 is arranged in the upper part of the latter in which plate a number of holes 10 all of the same size and arranged side by side along the length of the plate, are provided. A longitudinal slot, the various stretches of which are indicated in the drawings by the reference numerals 11¹, 10¹, 11², extends approximately over the whole length of the plate 9. Each of the slots 10¹ is common to two holes 10 with the exception of the holes in the series at the extreme right and at the extreme left. The depending stirrup-like base 5 of the coin container 4 embraces the dividing plate 9 in the manner shown in Figs. 1 and 3. At the lower end of the coin container 4, an oblique surface 8 is provided having the same slope as the inclined plane of the pusher 1 and which is practically flush with the dividing plate 9.

A pair of guide rails 12 is associated with each of the holes 10. These pairs of guide rails are fixed to the pusher 1 and a longitudinal slot 13 (Fig. 5) is provided between the two halves thereof. The various pairs of guide rails 12 are horizontally arranged and are stepped above each other in such a way that their ends lie one above each other at the right hand end, while they extend on the other side to the left hand edge of the associated hole 10. At the right hand end, the guides 12 are somewhat tapered (see Fig. 5) to enable a holder 16 to be fastened to them. The central axis of the slots 11¹, 10¹, 11² and 13 lie all in the same vertical plane.

To the vertical guides 3 for the coin holder 4 horizontal spindles 13¹ are fixed at both sides of the pusher 1 which serve to guide a frame 14 carrying a plate shaped ejector 15. When the pusher 1 is pulled to the left out of the position shown in Fig. 1, this ejector 15 passes successively through the slot 11¹, then the slot 10¹, then the slot 13 of the guide rails 12 and finally the slot 11². The above mentioned holder 16, as can be seen particularly from Fig. 6, has two hinged rack-forming wings which are urged towards each other by at least one spring arranged on one of the flaps of the hinge. Each of the rack-forming wings is sub-divided by cross pieces 17 (Fig. 6) into as many divisions as there are holes 10 formed in the dividing plate 9. The wings of the holder 16 are thus constructed as a kind of ladder. Such holders which are extremely handy, are cheap to construct and can be of unlimited length. The wings and their cross pieces can, for example, be stamped out of a steel plate.

The manner of actuating and the manner of operation of the described device are as follows:

Normally, the parts are in the position shown in Figs. 1 and 2. The coins of a particular size to be dealt with are placed in the groove of the trough 7, for which none of the special care has to be taken as is the case in the juxtaposed troughs or the troughs sub-divided by means of plates, in both of which the coins have to be arranged individually. When trough 7 is filled or

the balance of coins has to be determined at any time, trough 7 is tipped up towards the coin container 4 so that the coins fall out of the trough 7 into the hole 6 of the coin container 4. A holder 16 is then fastened to the tapered right hand ends of the pairs of guide rails 12 in such a way that the said ends come to rest on the cross pieces 17 of the holder 16. Hereupon, the wedge shaped pusher 1 is displaced, that is to say, moved towards the left, so that its inclined plane effects an upward movement of the coin container 4 in its vertical guides 3. This container 4, during the forward movement of the pusher 1, supplies a number of coins to each of the holes 10 arranged one behind the other in the dividing plate 9, as soon as the appropriate hole comes axially beneath the hole 6. The number of coins which can fall out of the hole 6 and remain piled therein in a group until the appropriate hole below is made accessible by the base 5 depends upon the distance between the inclined surface 8 and the base 5. This distance can correspond, for example, to the height of five piled coins of a particular unit. As soon as the base 5 has completely cleared the hole concerned below, the group of coins falls out of that hole on to the pair of guide rails 12 associated with the said hole, where it is first of all held by the ejector 15. Thus the coins which were fed in the described manner into the coin container 4 are divided up into groups of which each comprises the same number of coins. The thus formed groups are deposited on an associated pair of guide rails 12 during the same operative stroke. By means of the ejector 15 the different groups of coins are displaced along the horizontal pairs of guide rails 12 towards their tapered ends and are finally ejected into the corresponding division of the holder 16.

When the whole of the groups of coins have been transferred into the holder 16, the latter is removed from the guides 12 so that the wings of the holder tend to close and hold the groups of coins in the divisions associated with them. The coins divided up into groups thus remain in the holder 16 even after the latter is removed from the guide rails 12, neatly packed in subdivided groups and can be carried anywhere therein.

As, in the device described, the dividing up of the coins of the same size into groups and the subsequent packing of the said groups into the holder 16 are effected immediately one after the other and all that, moreover, is effected by a single operative movement, a large quantity of coins of a particular unit can be divided up and packed in such a device in the shortest possible time and without trouble.

Instead of joining the two longitudinal strips of the frame-like holder wings together by a number of transverse branches, it may be sufficient in certain circumstances to provide only short cross pieces as supports on said longitudinal strips for the groups of coins ejected into the holder.

For the coins which are used in Switzerland, for example, it is possible to manage with two or at the most three assemblies of the described kind. Preferably, one assembly can be provided for 0.01 franc, 0.05 franc and 0.50 franc coins, another assembly for 0.02 franc, 0.10 franc, 0.20 franc and 1.00 franc coins and one assembly for 2.00 franc and 5.00 franc coins. In such a case, as shown in Fig. 7, the different assemblies of the character described can be associated with a single base plate 20 in which the wedge-shaped

pushers 21, 22 and 23 of the three assemblies are longitudinally displaceable.

What is claimed is:

1. A device of the character described, comprising in combination a base plate; a wedge shaped pusher of right-angled triangle shape longitudinally displaceable in said base plate; a vertical guide fixed to the base plate, a coin container which can be displaced in said guide by said pusher; a longitudinally slotted dividing plate engaged in the upper part of the pusher and arranged parallel to the inclined plane of the latter, which plate has a number of holes arranged side-by-side in the direction of its length; a number of guide rails corresponding to the number of holes in said dividing plate, arranged beneath the latter above each other and slotted in the direction of their length, the ends of these rails at one side lying above each other and at the other side extending as far as the associated hole in said dividing plate; a stationary ejector carried by said base plate; and a holder adapted to be fastened to the ends of said guide rails which lie one above the other and which holder has a number of divisions corresponding to the number of holes in said dividing plate, said ejector, on displacement of said wedge-shaped pusher, passing through the slots which lie one above the other in said dividing plate and said guide rails and pushing thereupon the groups of coins falling out of said coin container through the holes in said dividing plate and which groups are all of the same height, into the divisions of said holder in which the coins can at all times be seen and counted.

2. The combination defined in claim 1 in which the base of the coin container embraces the dividing plate and together with an oblique surface of this container, which is practically flush with the inclined plane of the pusher, determines the height of the sub-divided groups of coins.

3. The combination defined in claim 1 in which the guide rails run horizontally and are arranged step-wise above each other.

4. The combination defined in claim 1 in which a trough having an open groove for receiving the coins to be packed and out of which the coins can be transferred into a cylindrical hole in the coin container is pivotally connected to this container.

5. The combination defined in claim 1 in which the vertical guide for the coin container is fixed to the base plate with a guide rail for the displaceable pusher.

6. The combination defined in claim 1 in which the ejector is connected to the vertical guide for the coin container.

7. The combination defined in claim 1 in which for the different groups of coins of a particular unit a separate wedge-shaped displaceable pusher is provided and all the pushers are associated with a common base plate.

8. The combination defined in claim 1 in which the holder for receiving the divided groups of coins has two rack-forming wings hinged together and urged towards each other by at least one spring.
